RALPH IMPROTA, OF PATERSON, NEW JERSEY, ASSIGNOR TO ROSENSTEIN BROTHERS,
OF PATERSON, NEW JERSEY, A CORPORATION OF NEW JERSEY.

"WOUND PACKAGE AND METHOD OF MAKING SAME.

Application filed June 23, 1923. Serial No. 647,358.

To all whom it may concern:

Be it known that I, RALPH IMPROTA, a citizen of the United States, residing at Paterson, in the county of Passaic and State 5 of New Jersey, have invented certain new and useful Improvements in Wound Packages and Methods of Making Same; and I do declare the following to be a full, clear, and exact description of the invention, such 10 as will enable others skilled in the art to which it appertains to make and use the same.

My invention relates to wound shuttle packages having a quill or other core for 15 the windings, and has reference more particularly to packages in which the windings are of tinsel, known as lame, or of other smooth, flat, hard filament having no fibres capable of intermingling with each other 20 and no elasticity to prevent the convolutions from slipping upon each other. Metallic wrappings of this nature have a great deal more weight than silk, cotton or wool threads and consequently possess more inertia, which characteristic, combined with 25 those above defined, has resulted in severe loosening of the wrappings upon the ordinary core or quill incident to the stopping and starting of the shuttle in the loom, causing 30 tangling and snarling of the filament and making it practically unusable. Considerable success with tinsel or lame has been obtained by winding only a relatively thin "shell" of the filament upon an enlarged core, but this type of package permits 35 the carrying of only a very small amount of the material on the core and consequently requires a great deal of time in removing cores and placing new packages in 40 the shuttles.

The cores to which I have referred are tapered or enlarged toward one end and the filament is wound back and forth thereon into superposed layers which are advanced 45 successively from the large end of the core or quill, but the packages so wound have the disadvantage above pointed out. It is therefore the principal object of my invention to provide a new method of winding lame or similar filament in such a manner 50 that a maximum amount of filament of the character mentioned may be placed upon the core but will have no tendency to loosen thereon or snarl, permitting it to be han-

dled by a shuttle as expeditiously as ordinary cotton, silk or wool thread. 55

In wound packages having superposed layers of windings built up upon each other in a more or less tapered formation, it has been customary heretofore to unwind the 60 strand by pulling it toward the smaller ends of the layers. This has a tendency to cause the layers to slip upon each other and tangle, so that it is a further aim of my invention to unwind in a different manner, overcom- 65 ing this difficulty.

With the foregoing in view, the invention resides in the novel subject matter herein-after described and claimed, the description being supplemented by the accompanying 70 drawings.

Figure 1 is a diagrammatic view exaggerated to show the relation of the numerous layers of windings.

Figure 2 is a diagrammatic elevaton 75 showing the manner of winding the first layer.

Figure 3 is a side elevation of a complete package formed in accordance with my invention. 80

While in winding quills in the past, it has been the practice to wind the strand back and forth forming a plurality of superposed layers while advancing the successive layers from the larger end of the core and 85 working toward the smaller end, in the practice of my invention, I reverse this operation and advance the successive layers of filament from the smaller end of the quill or core, working backward toward its base 90 so that the ends of the layers of winding adjacent the base will be supported by the cone or tapered portion of the quill and be prevented from slipping down on each other. 95

This method results in the ends of the layers of windings adjacent the small or outer end of the quill being securely held in position by the succeeding superimposed layers and in actual practice I have found that there is no tendency whatever of the filament knocking loose and snarling during the operation of the shuttle in the loom. While the core or quill 1 may be gradually tapered throughout its length, I prefer to make it as shown in the drawings with a small end 100 and a distinct enlarged or cone-shaped end or portion 2, which is substantially one-half the length of the quill. I have found 105

in practice that it is important to have the taper or cone portion with a slow taper, that is, with the surface of the cone at an extremely acute angle to the axis of the quill as clearly shown in Fig. 2. If desired, the smaller portion of the quill may be tapered somewhat toward the cone to permit the first few layers of windings to effectively cling to it but it may be made straight and provided with grooves 1^a for the same purpose. Both the taper and the grooves may however be used and both are illustrated in the drawings.

In winding the quill, it is placed in a suitable traverse winding machine and the strand or filament 3 is wound back and forth upon it, flat side contacting, into a plurality of superposed layers, while the successive layers are advanced longitudinally along the quill from the smaller end thereof. The first few layers of windings may be disposed entirely upon the smaller portion of the quill, terminating in slightly spaced relation from the enlargement 2, as indicated in Fig. 1, but the remainder engage or terminate upon this enlargement and are backed up thereby, so that said layers cannot bodily shift and permit the mass of windings to "break down" adjacent the enlarged end of the core. In other words, after one or more layers have been laid upon the smaller portion of the core, the remaining layers are carried beyond and around the inner ends of the preceding layers into engagement with the enlargement 2. As above indicated, this method of winding prevents any shifting of the convolutions at the other end of the core and although the package may be wound to maximum size, the forcible stroking and sudden stopping of a shuttle in which it is used will not affect its integrity in any manner whatsoever.

The winding operation above defined, produces a tapered formation to the numerous layers throughout portions of their lengths, as indicated at 5 and by placing the package in the shuttle in such a manner that the strand 3 will unwind by pulling toward the larger ends of these tapered portions of the layers, as indicated in Fig. 1, there is no tendency for said layers to slide one upon the other. However, it is not essential that the strand be pulled in this manner, as the package is so rigidly constructed that the strand may also be unwound by pulling in the other direction, without producing any serious results. This manner of unwinding has been indicated in Fig. 3.

It will be seen from the foregoing that I have greatly improved both the method of winding lame or other smooth hard flat filament and the construction of shuttle packages formed by carrying out the wind-

ing operation upon a core, and while the distinct improvements which I have made, will be clear from the foregoing, it may be well to summarize them as follows:—I take a core having a taper or a tapered enlargement at one end and wind the flat filament, flat side contacting, back and forth thereon, into a plurality of superposed layers, while advancing the successive layers from the smaller end of the core and carrying them into engagement with or building them up backwards and upon the cone or tapered portion. By so doing, I produce a shuttle package which will be entirely free of objections heretofore encountered when using any smooth, hard, flat strand which is liable to slip and snarl. I unwind the strand, preferably by pulling it toward the end of the core upon which the winding operation was started, which overcomes any liability of the conical portions slipping upon each other, but as above stated, it is not essential to pull in this direction. Specifically speaking, I have provided for the carrying of a maximum amount of lame or other smooth flat filament upon a core and have provided for successful, unimpaired use of this package in the shuttle of a loom, to permit the use of such filament as efficiently as any other material now commonly used in weaving.

The present disclosure is illustrative of the improvements above enumerated, but it is to be understood that within the scope of the invention as claimed, numerous changes might be made.

I claim:

1. The method of winding lame or other smooth, flat filament upon a core having an abutment at one end, consisting in winding the filament, flat side contacting, back and forth upon the core to form a plurality of superposed layers, while advancing the successive layers along the core from the smaller end toward the abutment thereof and carrying the inner ends of the layers into engagement with the abutment.

2. The method of winding lame or other smooth, flat filament upon a core having a cone-shaped portion and a smaller portion, consisting in traverse-winding a few layers of filament on the smaller portion terminating such layers short of the cone, then continuing the winding and working toward and up upon the cone to produce a body of winding having its outer surface tapered at both ends.

3. The method of winding lame or other smooth, flat filament upon a core having a portion tapered from one end, consisting in winding the filament, flat side contacting, back and forth upon the core to form a plurality of superposed layers, while advancing the successive layers along the core from the smaller end thereof, and carrying

- them beyond and inwardly around the inner ends of the preceding layers, thus building them up upon the tapered portion of the core.
- 5 4. An article of manufacture comprising an elongated core having a portion tapered from one end, and a comparatively thick mass of lame or other heavy smooth, flat filament wound flat on said core in a plurality of superposed layers, the ends of said layers at the smaller end of said core receding successively therefrom, and the other ends of said layers extending into engagement with the tapered portion of said core.
- 10 5. An article of manufacture comprising an elongated core having a portion tapered from one end, and a plurality of superposed layers of windings of lame or other smooth flat filament laid flat on said core, the ends of said layers at the smaller end of said core receding successively therefrom, and the other ends of said layers extending beyond and around the corresponding ends of the preceding layers and engaging the tapered portion of said core.
- 15 6. A wound package usable in a loom shuttle without disintegration and snarling under the starting and stopping of the shuttle, comprising a shuttle quill having a tapered peripheral surface at an extremely acute angle to the quill axis, and a relatively heavy "non-yieldable" metal mass solidly and anti-slippingly surrounding said quill and incapable of being disintegrated by the starting and stopping of the shuttle, said mass consisting of a filament of flat metal traverse-wound on said quill into layers gradually receding from the smaller end of the quill at one end of the mass and substantially all terminating on said tapered peripheral surface at the other end of said mass.
- 20 7. A method of unwinding a smooth flat filament from a quill or other core on which it is wound in a plurality of superposed layers which are advanced along the core from one end thereof, consisting in pulling the filament toward the end of the core from which the layers of windings are advanced.
- 25 8. The method of unwinding a smooth flat filament from a core on which it is wound back and forth in a plurality of superposed layers arranged in tapered formation, consisting in pulling the filament toward the larger end of the layers to prevent the latter from sliding one from another.
- 30 In testimony whereof I have hereunto affixed my signature.

RALPH IMPROTA.
